Primary Examiner — Wan Laymon

(74) Attorney, Agent, or Firm — Leana Levin; Douglas J. Hura; David A. Zdurne

CLAIM

The ornamental design for a dental device connection adapter, as shown and described.

DESCRIPTION

FIG. 1 is top view of a dental device connection adapter showing our new design;

FIG. 2 is a bottom view thereof;

FIG. 3 is a first side view thereof;

FIG. 4 is a second side view thereof;

FIG. 5 is a front view thereof; and,

FIG. 6 is a rear view thereof.

The broken line showing in FIGS. 5 and 6 is included for the purpose of illustrating portions of the dental device connection adapter that form no part of the claimed design.
